OSCILLATION GENERATOR

James J. Lamb, West Hartford, Conn., assignor
to Radio Corporation of America, New York,
N. Y., a corporation of Delaware

Application January 10, 1933, Serial No. 651,012

11 Claims. (Cl. 250—36)

My invention aims to provide improvements in electron tube oscillation generators.

In the drawing which illustrates preferred embodiments of my invention:

5 Figure 1 is a wiring diagram of an embodiment of my invention in the form of a circuit using an indirectly heated cathode type of electron tube; and

10 Fig. 2 is a wiring diagram showing my invention as adapted to a circuit including an electron tube of the directly heated cathode type.

15 My invention, as illustrated by the drawing, is particularly useful as a stabilized electron tube oscillation generator and my improved circuits are particularly desirable because they are free from feed-back coupling between the output and control-grid circuit. Therefore, there is practically complete isolation of the output circuit from the control-grid circuit because of electro-20 static screening of the inner anode which is maintained at ground radio-frequency potential. The output circuit is isolated from the oscillation generator circuit thereby preventing variations in the output circuit from affecting the frequency 25 of oscillation while permitting amplified output from the frequency generating circuit to be transferred to the output circuit by electronic means.

The particular circuit illustrated in Figure 1 includes a four element electron tube 1 containing an indirectly heated electron-emitting cathode 2, cathode-heating means 3, a control element or grid 4, an inner anode 5 and an outer anode 6. A circuit containing an inductance coil 7 and a variable capacitance 8 is connected between the cathode 2 and inner anode 5. In this circuit is also connected a fixed capacitance 9. Another circuit is connected between the control element 4 and the cathode 2 and in this circuit there is located a crystal substance 10 such as quartz and the like having piezo-electric properties. This circuit also includes a suitable resistance 11 in parallel with the crystal substance 10. The outer anode 6 is connected to the first described circuit at a point in that circuit common to the inductance 7, the variable capacitance 8 and the fixed capacitance 9. In this circuit is included an impedance or resistance 12 in series with a fixed capacitance 13, and the circuit is also connected to ground, as indicated, thereby also maintaining the inner anode at radio frequency ground potential. The output circuit is connected to the last described circuit at opposite sides of the resistance 12 and includes a condenser 14 of suitable value.

55 The cathode-heating means 3 may be supplied

with energy from any suitable means 15 and the circuit connected between the supply 15 and cathode-heating means 3 is maintained at substantially the same alternating current potential as the potential at the point of connection 5 between the circuit containing the condenser 13 and the circuit containing the condenser 9. To accomplish this result I use fixed capacitances 16 having low reactance at the generated frequency.

The plate supply means 17, together with the 10 resistance 18, is connected into the circuits in the usual manner for supplying the proper plate and grid potentials. The control grid 4, by means of the resistance 11, is maintained at an average potential which is substantially negative as compared with the cathode 2.

15 Referring now to the particular embodiment of my invention illustrated in Fig. 2, I have shown a circuit which includes an electron tube 19 having a directly heated cathode 20, instead of the 20 indirectly heated cathode 2 of the circuit shown in Fig. 1. Aside from the difference in the tube cathode, the circuit is substantially the same as that illustrated and described in connection with Fig. 1 with the necessary changes in the cathode-25 heating circuit.

All of the elements shown in connection with the circuit illustrated by Fig. 2 which are the same as those shown and described in connection with the circuit illustrated by Fig. 1 have been 30 given the same identifying numerals as those used in describing the circuit shown in Fig. 1.

35 My invention, whether embodied in the circuit shown in Fig. 1 or that shown in Fig. 2, is particularly desirable, because it has many advantages over other circuits using the oscillating properties of piezo-electric substances of which I am aware. Heretofore there has been a feed-back coupling from the output to the control-grid circuit which interfered with stability of 40 operation of the device as an oscillation generator. My improved circuit is particularly stable in operation because of the fact that the oscillation generating circuit, comprising the control-grid 4, inner anode 5 and cathode 2, is isolated from 45 variations arising in the output circuit. In operation, my circuit differs from those of which I am aware because the adjustable tuned circuit may be varied in value over a substantially wider range of inductive reactance while persisting in 50 oscillation at the frequency determined by the piezo-electric substance 10. In this wide range of tuned circuit inductive reactance values the frequency of oscillation is more independent of 55 changes in circuit values and tube characteristics.

Furthermore, my circuit, whether using the type of tube shown in Fig. 1 or that shown in Fig. 2, possesses inherent dynamic self-stabilization properties such that proportional changes in the inner and outer anode-supply voltages have substantially less effect on the frequency of oscillation than is the case with other known circuits. Also, my circuit has substantially greater output at frequencies harmonically related to the frequencies of the stabilizing piezo-electric substance 10. These advantages are almost entirely due to the fact that the inner anode 5 is arranged to provide electro-static screening maintained at ground radio-frequency potential thereby preventing the output circuit from affecting the frequency of oscillation in the oscillation generating circuit. For instance, the harmonic generating ability results from the equivalence to two tubes performing the separate functions of oscillation generation and distorting amplification. The oscillation generating circuit, including control grid 4, cathode 2 and inner anode 5, performs as a triode of low amplification factor. The harmonic generating circuit includes those same elements and also the outer anode 6, with cathode 2 and control grid 4 common to both, and with the inner anode 5 serving simply as a screen grid between those elements and the outer anode 6. This harmonic generating circuit is equivalent to a four-element tube of high amplification factor. Since the bias and excitation to a high- μ screen grid tetrode are determined by the operation of the triode generating circuit that is common to both, the bias and excitation are high for the tetrode, thereby satisfying the conditions for distorting operation and harmonic generation.

Some of the important advantages of my invention over other known circuits for oscillation generators may be summarized as follows:—

Oscillation persists over a substantially greater range of tuning of the circuit including the inductance 7 and variable capacitance 8 when adjusted to have inductive reactance for the resonance frequency of the piezo-electric substance 10.

When the circuit including the inductance 7 and capacitance 8 is adjusted as just described variations in circuit capacitance, inductance and resistance values and in electron tube characteristics have substantially less effect on the frequency of oscillation.

Variations in anode voltages and cathode temperature have less effect on frequency of oscillation.

Output of frequencies having harmonic relation to the frequency of oscillation is very much increased.

Departure from normal output circuit conditions has no appreciable effect upon the frequency of oscillation.

While I have illustrated and described preferred embodiments of my invention, I do not wish to be limited thereby, because the scope of my invention is best defined by the following claims.

I claim:

1. An oscillation generator of the class described including an electron tube having a cathode, a control element, an inner anode and an outer anode, a radio frequency ground connection to said inner anode, a circuit connected between the cathode and inner anode and including inductance and capacitance, a crystal substance connected between the control element and the cathode, a resistance in parallel with said crystal connection, a circuit connected to the

outer anode and the first mentioned circuit and including an impedance and a capacitance and an output circuit connected to the last mentioned circuit and being isolated from the oscillation generating circuit because of the electrostatic screening of the inner anode thus preventing the variations in the output circuit from affecting the frequency of oscillation of the generator.

2. An oscillation generator of the class described including an electron tube having a cathode, a control element, an inner anode and an outer anode, a radio frequency ground connection to said inner anode, a circuit connected between the cathode and inner anode and including inductance and variable capacitance, a crystal substance connected between the control element and the cathode, a resistance in parallel therewith, a circuit connected to the outer anode and the first mentioned circuit and including an impedance and a capacitance and an output circuit connected to the last mentioned circuit at opposite sides of said impedance and being isolated from the oscillation generating circuit because of the electro-static screening of the inner anode thus preventing the variations in the output circuit from affecting the frequency of oscillation of the generator.

3. An oscillation generator having an electron tube provided with a cathode, a control element, an inner anode and an outer anode, an oscillation generating circuit comprising said cathode, control element and inner anode having a piezo-electric substance connected between the control element and cathode and including inductance and capacitance, an output circuit connected at one side thereof to said outer anode and at the other side thereof to said inner anode, whereby said inner anode is common to both circuits, and means for maintaining said inner anode at radio frequency ground potential for isolating said circuits from each other.

4. A constant frequency generator comprising an electron discharge device having an anode electrode, a grid electrode, and a cathode, said cathode comprising a heated surface electrode and a heating element, an electromechanical vibrator connected between two of the electrodes of said device, a high frequency output circuit connected between two of the electrodes of said device, and a high frequency impedance connected between said heated surface electrode and ground, whereby the heated surface electrode fluctuates in potential at a frequency corresponding to the frequency of vibration of said electromechanical vibrator.

5. An oscillation generator having an electron tube including a cathode, a control element, an inner anode, and an outer anode, a piezo-electric substance, the latter connected between said control element and cathode, means constituting an inductive reactance, circuit means connecting one terminal of the latter to said cathode and connecting the other terminal thereof to said inner anode and outer anode, and means for maintaining the last mentioned terminal of said inductive reactance at radio frequency ground potential.

6. An oscillation generator comprising an electron discharge device having a cathode, and a plurality of cold electrodes, including a grid, screen grid and plate, a mechanical vibratile element connected between said cathode and said grid, a tuned circuit connected between said cathode and said screen grid and a load circuit connected between said cathode and said anode, said

screen grid circuit including a condenser and a ground connection thereto whereby to effectively ground said screen grid at the frequency of oscillation of said generator.

- 5 7. An oscillation generator of the class described including an electron tube having a cathode, a control element, an inner anode and an outer anode, means for maintaining said inner anode at substantially zero radio frequency potential, a circuit connected between the cathode and inner anode and including inductance and capacitance, a piezo-electric crystal connected between the control element and the cathode, a resistance in parallel therewith, a circuit connected to the outer anode and the first mentioned circuit and including an impedance and a capacitance and an output circuit coupled to the impedance of said last mentioned circuit and being isolated from the oscillation generating circuit because of the electro-static screening of the inner anode thus preventing the variations in the output circuit from affecting the frequency of oscillation of the generator.

- 25 8. An oscillation generator having an electron tube including a cathode, control element, inner anode and outer anode, an oscillation generating circuit comprising said cathode, control element, inner anode, a piezo-electric control element, an inductance and a capacitance, in which circuit said control element of said tube is connected through said piezo-electric control element to said cathode and the latter is connected through said inductance and capacitance to said inner anode, an output circuit comprising said outer anode and a second capacitance, in which output circuit said outer anode is connected through said second capacitance to a point on said first mentioned circuit intermediate said inductance and capacitance and said inner anode, and a radio frequency ground connection to said point whereby said second mentioned circuit is shielded from said first mentioned circuit by said inner anode.
- 40 9. An oscillation generator having an electron tube including a cathode, control element, inner anode and outer anode, an oscillation generating circuit comprising said cathode, control element,

inner anode, a piezo-electric control element, an inductance and a capacitance, in which oscillation generating circuit said control element of said tube is connected through said piezo-electric control element to said cathode and the latter is connected through said inductance and capacitance to said inner anode, an output circuit comprising said outer anode, an impedance, and a second capacitance, in which output circuit said outer anode is connected through said impedance and said second capacitance to said first mentioned circuit at a point in the latter between said inductance and capacitance and said inner anode, a radio frequency ground connection to said point whereby said second named circuit is shielded from said first named circuit by said inner anode, and an output circuit connected across said impedance.

10 10. An oscillation generator having an electron tube including a cathode, a control element, a first anode, and a second anode, a piezo-electric substance, a tuned circuit including capacitive and inductive reactance, circuit means connecting said substance between said control element and cathode, circuit means connecting one terminal of said tuned circuit to said cathode, said last two circuit means having a portion in common, means connecting the other terminal of said tuned circuit to said first anode and to said second anode, and means connecting said other terminal of said tuned circuit to a point of substantially ground radio frequency potential.

15 11. An oscillation generator having an electron tube including a cathode, a control element, a first anode, and a second anode, a piezo-electric crystal connected between said control element and cathode, a circuit comprising parallel reactances, means connecting one terminal of said circuit to said cathode and connecting the other terminal of said circuit to said first anode and to said second anode, means connecting the other terminal of said circuit to a point of substantially ground radio frequency potential, and means for impressing a negative bias on said control element relative to said cathode.
